BY *Henry S. DeWitt*
ATTORNEY

UNITED STATES PATENT OFFICE

JOHN L. McLAY, OF SACRAMENTO, CALIFORNIA

SPEED WRENCH

Application filed June 30, 1930. Serial No. 464,821.

This invention relates to mechanics' hand tools, and particularly to a wrench of that type known as the speed wrench and which is usually used to advance or retract nuts from bolts or studs, up to the final tightening or after the initial starting or loosening of the nut respectively; and by means of which as the name implies, such nut turning operations are effected more rapidly than can be done with the ordinary "monkey" or solid wrench.

The principal object of my invention is to provide a wrench of this character so constructed that it may be held and the desired speedy rotation of the same efficiently effected by one hand of the operator after a little practice, thus leaving his other hand free for other purposes, such as initially holding the nut in position relative to the bolt, when inverted or in a relatively inaccessible position.

A further object of the invention is to construct the wrench so that it may not only be used for speedy turning of the nut when the latter is relatively free, but may be also quickly and easily adjusted so that the necessary leverage is obtained to effect a starting or final tightening of the nut.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Fig. 1 is a side elevation of my improved wrench showing the same in position to be used as a speed wrench.

Fig. 2 is a similar view showing the wrench as adjusted for use to effect a starting or final tightening of a nut.

Referring now more particularly to the characters of reference on the drawings, the numeral 1 denotes a relatively short shank which is squared on one end as at 2 to removably fit the socket 3 formed in one end of a standard extension stem 4, which stem on

its other end carries a nut engaging socket 5 of common character. The other end of the shank has a head 6 on which is pivotally mounted a fork 7. Formed with this fork is a crank which comprises another shank portion 8 projecting from the fork radially of the pivotal pin 9 of the head and fork, said shank 8 at its opposite end being bent to form a relatively long spindle 10 disposed at right angles to the shank portion 8. A handle 11 is turnable on the spindle, the length of said handle being such that its outer end will project a short distance beyond the axial line L of the shank 1 when said handle is disposed at an angle of approximately 30 degrees to said line, or when the shank portion 8 is accordingly disposed at a 60 degree angle to said line.

It is this position of the handle relative to the shank 1 that permits the latter to be speedily rotated by one hand grasping the handle without any material wobbling motion being imparted to the shank such as would prevent the effective use of the tool for its purpose. The handle is releasably maintained in such position by a spring pressed pin 12 slidably mounted in the shank 8 radially of the pivot 9, and engaging a recess 13 cut in the periphery of the head 6.

When it is desired to use the wrench for nut starting or tightening purposes, the shank 8 is turned about the pivot 9 as an axis, so that both shanks are longitudinally alined, when the handle 11 will be disposed at a right angle to the shanks as will be evident. Owing to the relatively great length of the handle this position of the latter provides a good leverage for a turning movement of the shanks and of the nut engaged by the holding extension. To releasably maintain the handle in this position the head 6 is provided with another recess 13a for engagement with the pin 12.

The handle member may be turned in the same direction until it lies parallel to the shank 1, as shown in dotted lines in Fig. 2. With this positioning of the parts the wrench is in a relatively compact form so as to occupy a minimum of space when not in use.

From the foregoing description it will be

readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A speed wrench comprising a straight rigid shank having a part engaging element on one end, another straight shank member, a handle rigid with said shank member on one end and disposed at right angles thereto, means pivotally connecting the shanks at their ends opposite said element and handle, and means associated with the pivot connection to hold the shanks in longitudinal alignment with each other so that the handle extends at right angles to the first named shank; so that the shank member is disposed at an obtuse included angle with the first named shank with the handle projecting toward the extended axial line of said first named shank; or so that the shank member is disposed at right angles to the first named shank with the handle parallel to and alongside the same, selectively.

In testimony whereof I affix my signature.

JOHN L. McLAY.
